CHAIR WITH DETACHABLE FOOTREST

Morton D. Rechler, New York, N. Y., assignor to
Exart Metal Industries, Inc., New York, N. Y.,
a corporation of New York

Application February 11, 1950, Serial No. 143,679

3 Claims. (Cl. 155—165)

1

This invention relates to chairs, and particularly to means for detachably connecting a footrest to the front portion of a chair frame.

Heretofore, it was the practice to provide a foot-rest with a pair of hooks which engaged over the cross bar of the seat frame to hold the foot-rest in place. That type of attaching means was objectionable because the hooks did not afford a positive connection and were subject to easy accidental uncoupling.

Accordingly, it is one of the objects of this invention to provide connections of a more positive nature to insure that the foot-rest will remain in place until voluntarily uncoupled from the chair.

Another object is to provide a foot-rest frame having elastic properties which are utilized to hold the connecting means in operative position.

Another object is to provide a foot-rest which is easy to couple and uncouple from the chair by simple manipulation of the elastic frame, and foldable to occupy small space when not in use.

A further object is to provide a foot-rest of pleasing appearance, contoured for comfort, and in which the parts will not catch in the clothing.

Other objects and features of advantage will appear as the description proceeds.

In the drawings of this specification:

Fig. 1 is a perspective view of my new footrest in combination with a chair.

Fig. 2 shows the foot-rest detached and folded.

Fig. 3 is a plan of the foot-rest connected to the front edge of a seat frame, parts being broken away in section.

Fig. 4 is a sectional detail of the catch and slot connection shown in Fig. 3.

Fig. 5 is a cross-section on the line 5—5 of Fig. 4.

Fig. 6 is a cross sectional view of a slightly modified form of catch means.

Fig. 7 is a detail of a slotted chair frame.

Fig. 8 is a further modified form of slot and catch connection embodying the invention.

In the drawing there is shown in Fig. 1 a chair 10 which includes a seat frame 11 having a front cross member 12 adapted to support the two ends 13 and 14 of a foot-rest 15. The outer end 16 of the foot-rest is held in its position of use by a pivoted supporting frame 17.

The foot-rest 15 is formed from a length of tubular metal stock bent to provide a U-shape frame 18 having the side rails 19 and 20 which are adapted to spring outward from each other as indicated by the arrows A to bring the neck 55 rounded convexity 44, and the cover 35 con-

portions or notches 21 of headed catch elements 22 into engagement under spring pressure with the edges 23 formed at the ends of spaced slots 24 provided in the outer wall 25 of the tubular cross member 12 of the seat frame 11. With the catch elements 22 thus engaged the two ends 13 and 14 are positively connected to the framework of the chair and can be released only by forcing the two ends toward each other against the spring of the frame 18 sufficiently to allow withdrawal of the elements 22 from the slots 24.

The headed elements 22 may be stamped or otherwise cut from flat metal sheet and are preferably formed with a body portion 26 for reception in the ends 13 and 14 and may be secured by a rivet 27 passed through body portion 26, a pair of filler blocks 28, and openings 29 in the respective ends of the frame 18. As shown in Fig. 4 the headed elements 22 may be of dart-like formation with shoulders 30 and 31 disposed behind the inner wall surface 32 of the cross frame 12, to hold the catch in place. In this way the neck portion 21 acts in the capacity of a holding notch.

The similar neck portion or notch 33 at the opposite side of the catch element 22 is adapted to engage the edge 34 at the other end of slot 24 when excessive load is placed upon cover 35 forcing the rails 19 and 20 toward each other against the spring action of the frame.

In the modified construction shown in Fig. 6 the catch element 22 has a slightly different shape to fit the rounded contour 12' of a seat frame having the slots 24 spaced farther apart.

In Fig. 8 a U-shape metal piece 36 is attached to the cross member 37 by riveting as indicated at 38, and has a pair of slots as previously described, one of which is shown at 39 in this modification. It is thus possible to use the catch mechanism in connection with a cross frame of solid material such as wood.

Preferably the body portions 26 and the ends of side rails 19 and 20 are curved away as at 40 to present smooth surfaces which will not catch in the clothing.

The outer end 16 of frame 18 is pivoted to the upper ends 41 of supporting frame 17 by suitable fastening means such as bolts 42 which pass through the side rails 19 and 20. This enables frame 17 to be opened to its operative position shown in Figs. 1 and 3, or closed to the folded condition seen in Fig. 2. Spacers 43 may be used between rails 19, 20 and ends 41.

It will be noted that frame 18 has an upwardly rounded convexity 44, and the cover 35 con-

forms to this curvature. This gives additional comfort to the foot-rest and grace of line to the framework. When the foot-rest is open for use the bottom rail 45 of support 17 rests upon the floor. Support 17 may be preferably a U-shape frame having the rising side members 46 terminating in the ends 41. The side members 46 are bent at 47 giving the upper portions of this frame a slight angulation with respect to the lower portions. This enables the upper portions 10 48 to contact the under sides 49 of the downwardly curving outer end 16 while the lower portions of frame 17 extend to the floor at less angulation.

It is seen in Fig. 2 that the supporting frame 17 folds into the concavity 50 formed by the curvature of the side rails 19, 20, and extends under the curved cover 35 which spans the rails. The cover may consist of duck or other suitable material stitched at 51 to form loops 52, 53 engaging the rails.

This foot-rest is adapted for connection to any suitable chair, and in the present instance is shown applied to a sun chair having the seat frame 11, front and rear legs 54 and 55, back frame 56, arm rests 57, and a seat covering 58 which extends from the top of the back frame to the front cross member 12 of the seat frame. The slots 24 may be located slightly beyond the side edges 59, 60 of the seat covering 58. The foot-rest frame 15 may be of any material having a sufficiently springy quality to expand the rails 19 and 20 outward from each other after they have been slightly compressed against the spring action to enter the headed elements 22 in the slots 24. Cold drawn aluminum tubing is suitable for this purpose and has the advantage that it is light. The headed elements 22 may be secured to the terminal ends 13 and 14 in other ways such as by welding, and may be of various forms to detachably interlock with the slots in the chair frame. Also, the spring frame may be made to operate in the reverse direction to the arrows A, and other modifications may be made in the arrangement of the parts. It is to be noted in Fig. 5 that the top of cross member 12 be flush with the top surface of rail 20. This gives the framework a smooth upper surface next to the clothing. The cover 35 is designed to allow free manipulation of the spring frame during coupling and uncoupling of the headed elements 22 in the slots 24 and is preferably drum tight between the rails when the foot-rest is in its position of use on the chair. The frames are preferably of rectangular cross section although this is not essential. The 55 rectangular tubing is used because it is more pleasing in appearance and is somewhat easier to process. If it is desired to use the spring frame to operate the side rails in the opposite direction, that is, toward each other instead of away from each other, the slots can be spaced accordingly to

interlock with the heads. In that case the cover may be made loose enough to allow the necessary frame manipulation to enter the heads into the slots. The cover may also have elastic webbing or elastic threads in its weave to permit stretch and to take up slack. Various other modifications may be made within the scope of the appended claims.

I claim:

1. In combination, a chair having a front cross member provided with horizontal spaced slots, a U-shaped spring frame forming a foot-rest and having oppositely disposed side rails which are adapted to spring apart, a fabric cover spanning the side rails, the terminal ends of the side rails being provided with notches which notched terminal ends enter the slots and are forced laterally in opposite directions against the outer ends of said slots when the side rails are released and spring apart, said fabric cover being brought to drum tight condition when said notched terminal ends are in spring pressed engagement against the outer ends of the slots.

2. In combination, a chair having a front cross

25 member provided with horizontal spaced slots, a U-shaped spring frame forming a foot-rest and having oppositely disposed side rails which are adapted to spring apart, a fabric cover spanning the side rails, the terminal ends of the side rails being provided with notches which notched terminal ends enter the slots and define portions which are forced laterally in opposite directions against the outer ends of said slots when the side rails are released and spring apart, said 30 fabric cover being brought to drum tight condition when said portions are in spring pressed engagement against the outer ends of the slots, said terminal ends being also provided with a second set of notches which define portions located to engage the opposite ends of said slots in the event that the first named portions are accidentally withdrawn as by excessive weight on the cover.

3. A combination according to claim 2 wherein 35 said first named notches are located opposite the second named notches in the outer edges of flat dart-like members adapted to enter the slots.

MORTON D. RECHLER.
